Inventor:
Allister S. Mitchell,

H. C. Schroeder
Atty.

UNITED STATES PATENT OFFICE.

ALLISTER S. MITCHELL, OF OAKLAND, CALIFORNIA, ASSIGNOR TO CALIFORNIA COTTON MILLS COMPANY, OF OAKLAND, CALIFORNIA, A CORPORATION OF CALIFORNIA.

PADDING.

Application filed October 25, 1923. Serial No. 670,716.

To all whom it may concern:

Be it known that I, ALLISTER S. MITCHELL, a citizen of the United States, residing at Oakland, in the county of Alameda and State of California, have invented certain new and useful Improvements in Padding, of which the following is a specification.

My invention is an improved padding primarily designed for padding the upholstery 10 of an automobile, and is a continuation in part of my co-pending application #564,705, filed May 31, 1922. This application is also a divisional application of case #670,717 filed of even date herewith.

The padding now used in the upholstery of automobiles consists of a fibrous material placed beneath the outer cover of the seat. The fibrous material has in the past been inserted by various means such as by sizing 20 the material on both sides, drying the same, cutting the material into proper lengths, folding to the proper width, and then inserting the same beneath the covers of the seat. This entails considerable waste of material 25 and labor.

My padding is formed complete in one operation and is made into a substantially tubular form of many yards in length, so that the same may be inserted into a proper 30 instrument, the instrument inserted into the pleats of the seat, the instrument being then withdrawn, the padding sliding through the instrument and the padding being then cut or torn to the proper length, so that practically no material is wasted.

In order to increase the tensile strength of the padding, I find it advisable to reinforce the padding by means of a strip of relatively strong paper. The paper further 40 serves as a means for holding the padding in proper form, which form is preferably tubular.

One of the objects of having the padding in tubular form is to increase the resiliency 45 thereof.

Other objects and advantages of this invention will appear upon a reading of the following description.

Referring to the annexed drawing, in 50 which my invention is illustrated and which forms a part of this specification:

Figure 1 is a perspective view of my improved padding.

Fig. 2 is an end view of my padding folded into its finished form and having its 55 edges secured by means of a strip of paper.

Fig. 3 is an end view of a modification.

My padding consists of a sheet of light weight fibrous material 1, which material may be cotton or other suitable padding. 60 The sheet 1 is folded into a somewhat tubular form, as illustrated in Figs. 1 and 2, so that the edges thereof will be lapped. Between the lapped edges, I insert a long strip of paper 8, having an adhesive 10 on both 65 sides. The edges of the sheet 1 are then pressed against the strip of paper 2, so that the edges are secured permanently by the adhesive 10.

In Fig. 3, the sheet 3 is provided with a 70 double fold, as illustrated, having a strip of adhesive paper 8 inserted between the adjacent folds.

In either case, the paper serves as a means for permanently uniting the padding into a 75 somewhat tubular form, the fibrous material making the same resilient and the strip of paper adding tensile strength thereto.

In the specification and claims, where I have used the word "tubular" as describing 80 the shape of the finished article, I do not mean that the article is perfectly round or that there is at all times any space between the adjacent layers of the folded article. In using the words "tubular form," I mean 85 that the lower layer of the padding is not held rigidly against the upper layer or layers, which structure is shown in each of the figures of the drawings.

While I have shown two specific forms of 90 my invention, it is obvious that many variations might be made without departing from the spirit of this invention. I, therefore, do not limit myself to the particular forms shown except as I might limit myself in the 95 annexed claims.

I claim:

1. A padding comprising a sheet of resilient material folded into substantially tubular form and a strip of material placed between the adjacent edges of said resilient material and having an adhesive on both sides thereof, said resilient material adhering to the sides thereof.

2. A padding comprising a sheet of fibrous 105 material folded into substantially tubular

form and means whereby tensile strength is added to said fibrous material, said means comprising a strip of material having an adhesive on both sides thereof adapted to permanently hold the fibrous material into tubular form.

3. A padding comprising a sheet of soft

material and a strip of strong material having both sides thereof glued, said soft material being folded into substantially tubular 10 form and held in position by means of the glue and the strong material.

In testimony whereof I affix my signature.

ALLISTER S. MITCHELL.
